Horse Power

Patented July 21, 1831.

6659 X July 21, 1831 2017

Nichoniah P. Stanslowe
Sect. 1. Patent

The Subscriber referred to in these Letters Patent and making part of the same containing a description in the words of the said Nichoniah P. Stanslowe himself of his improvement in the Threshing Machine together with the application of Horse Power for operating said machine

To all to whom these presents shall come. Be it known that I, Nichoniah P. Stanslowe of the village of Dryden in the County of Oneonta State of New York have invented a new and useful improvement in a machine for threshing grain & the Horse Power to operate said machine. In which Horse power may be applied to all other uses and purposes to which Horse power is or may be applied and that the following is a full and exact description of the construction & operation of the said machine & Horse Power as invented or improved by me. Said machine is constructed with a frame five feet long three feet five inches wide & two feet four inches high made with four posts, two plates, two sets of guides or crop timbers, with a brace from the foot of each forward post to the top of each back post calculated to receive the grain in concave bed which is to be made of hard wood planed ^{flat} facing with wrought iron three fourths of an inch wide & three sixteenths of an inch thick to be fastened on with screws a said bed may be lined with a cast iron concave plate planed as aforesaid. The bed stands on four spiral springs placed between the said braces by the bed for the purpose of suffering hard substances to drop between the bed & cylinder without injuring either. The length of the bed may be about two feet six inches & the width may be twelve inches faced with iron where the grain enters the machine. The bed is to be geared by keys, passing thro' arms which extend from the bed through the spring & braces. The cylinder is to be the same length of the bed made round of solid hard wood nine sixteenths diameter with an iron shaft running through it in each end a half square with a bearing at each end of the cylinder one end of the shaft runs far enough out to receive a wheel of about six inches diameter. There are six wooden teeth or research & three quarters thick & two and one half inches in running length of the cylinder

cylinder & ground in iron to project over each a long experienced workman
 & found on the side towards the hopper with wrought iron plates two inches
 wide & three sixteenths of an inch thick secured by screws or rivets. There are
 twenty-four spikes between each border made of wrought iron half an inch
 square with a lower cut on one end & drawn to a square point at the other which
 are to be forced into the cylinder so as to project two inches. They are to be
 set in the coarse space forming a cylinder with eight borders & one hundred
 and fifty spikes. The ends of the cylinder are secured by iron bands. The cy-
 linder projects into the coarse or circular bed before described & is covered with
 a circular cap of sheet iron. There is a facing table with a throat to receive
 the grain & directly over it a throat to discharge the dust. The improve-
 ment which I claim in the above Thrashing machine is the construction &
 working of spikes & borders on the same cylinder with the addition of a coarse bed,
 the head iron cap & the construction of the dirt discharge. The description &
 specification of the Horse power above mentioned is as follows. The frame is to
 be nine feet long & eight feet wide & three feet high with three sides, three
 plates, six posts and two girds. The frame contains the following gear-
 ing. One crown wheel six feet diameter with open gearing of each side with
 iron core shaft, arms and gear. The shaft is two feet eight inches long & stands
 perpendicular to the ship girder on the lower end which step into a box in
 the middle sill with a ring gear on the top with a neck passing thru
 the middle plate, on the top of the neck is a diamond head upon which
 the lower is let on to by means of a mortice in the centre. The whole length of
 the lower is nearly four feet. it is made eight inches square in the mid-
 dle & tapers to three inches square at each end. Each crown wheel meshes
 into a low side pinion on another upright shaft stepped onto the same
 sill at the bottom & carrying in a box in the same place of the top with the
 crown wheel shaft. The shaft of the pinion wheel is regulated by keys of the
 top & bottom so as to mesh in & out with the crown wheel as may be re-
 quired. On the shaft of the pinion wheel is also a hand wheel about four inches
 in diameter upon arms, which meshes into an eight inch pinion wheel on
 another shaft carrying four iron cast iron bars black iron of which is
 sometimes into a blunt wedge the other will be in form of a square to form a

with loops on which last mentioned shaft is attached a three foot beam with band wheel from which a band or strap is taken to a pulley which pulley having this it is a shaft the quergang of which over the loops projects eight inches below the path of the horses and between the machine & horse power frame on the side of and adjoining which pulley is a thirty inch pulley from which a band is taken to the wheel or pulley on the threshing machine. On bridge is built over the pulley two steps which are elevated under the horses path. I also claim as my invention or improvement the construction of the gearing of this horse power to run beneath the lever by which the horses draw, also the placing said horse power firm & substantialy on the ground & the communication between the threshing machine and horse power under the walk of the horses by means of bands, straps, ropes, chains, or shafts. I also claim as my invention or improvement the lever passing around over the top of the frame of the horse power and the second quergang projecting above the outer plate of the horse power to which said lever is attached. June 20 1831.
